United States Patent Office

Des. 223,456
Patented Apr. 18, 1972

223,456

ANTENNA

Edward Finkel, New York, N.Y., assignor to JFD
Electronics Corporation, Brooklyn, N.Y.

Filed Oct. 28, 1970, Ser. No. 22,930

Term of patent 14 years

Int. Cl. D14—03

U.S. Cl. D26—14

The figure is a perspective view of an antenna showing my new design.

The undisclosed rear side is unornamented.

I claim:

The ornamental design for an antenna, as shown and described.
